(57) **CLAIM**

The ornamental design for a corner and side hole punch, as shown and described.

DESCRIPTION

FIG. 1 is an assembled top perspective view for a corner and side hole punch showing my new design;

FIG. 2 is a top side view thereof;

FIG. 3 is a front side view thereof;

FIG. 4 is a bottom side view thereof;

FIG. 5 is a back side view thereof;

FIG. 6 is a left side view, the right side view being a mirror image thereof; and,

FIG. 7 is an exploded top perspective view thereof.

The broken lines in the drawings depict unclaimed environmental subject matter.
